JOSEPH GIULIANA, OF NEWARK, NEW JERSEY.

ELECTROPLATING APPARATUS.

1,291,830.

Specification of Letters Patent. Patented Jan. 21, 1919.

Application filed November 1, 1917. Serial No. 199,744.

To all whom it may concern:

Be it known that I, JOSEPH GIULIANA, a citizen of the United States of America, and a resident of Newark, in the county of 5 Essex and State of New Jersey, have invented new and useful Improvements in Electroplating Apparatus, of which the following is a specification.

This invention relates to that class of 10 electroplating apparatus which employs a barrel in which a plurality of small articles are placed loose and tumbled about during the application of current thereto.

The objects of this invention are to provide 15 a plating apparatus of this sort which can be manipulated readily by one man; to avoid unnecessary exposure of the cathode or conductors thereto within the solution; to provide a cathode which can be removed 20 for cleaning or the like; to obtain positive and continuous contact of the cathode with the articles to be plated with minimum exposure of said cathode; to provide a hard surface for the articles to tumble 25 upon and a permeable end toward the anode for the ready passage of current; to mount the apparatus conveniently in the tank; to secure simplicity of construction and operation, and to obtain other advantages 30 and results as may be brought out in the following description.

Referring to the accompanying drawings in which like numerals of reference indicate the same parts throughout the several views, 35 Figure 1 is a perspective view of an electroplating apparatus embodying my invention;

Fig. 2 is a vertical section of the same showing it mounted in a tank; 40 Fig. 3 is a sectional view on line 3—3 of Fig. 2 with the head of the barrel removed, and

Fig. 4 is a section upon a plane substantially midway between the ends or heads 45 of the barrel showing the electrical contact from the center of the barrel to the cathode.

In the specific embodiment of the invention illustrated in said drawings, the reference numeral 1 indicates a barrel, shown as 50 cylindrical, with a series of gear teeth 2 around its periphery. These gear teeth mesh with the teeth of a pinion 3 upon a stud shaft 4 which in turn is driven by a belt 5, or other suitable means, passing around a pulley 6 on said shaft. The barrel 1 and stud shaft 4 are both carried upon

a post 7 which in use is stood upright in a tank 8, and it is with the apparatus in this upright position that the belt 5 is applied to the pulley 6, for rotating the barrel from 60 the stud shaft 4 by virtue of the pinion 3 on said shaft meshing with the teeth 2 on the drum.

The drum is rotatably mounted upon an axle 9 shown projecting transversely from 65 the post 7 and shown as an integral part of a conductor bent at its opposite ends with its middle portion 10 extending longitudinally upward within the post, its lower end projecting laterally from said post to form 70 the said axle and with its upper bent end 11 projecting from the post near the top thereof. Preferably this upper end 11 extends in the same general direction as the lower end or axle and is provided with a 75 shoe 12 transverse to said end 11 adapted to rest upon the usual cathode rod 13 horizontally disposed at the top of the tank. Current will therefore be taken from the cathode rod 13 through the upper extension 80 11 of the conductor, vertical portion 10 within the post 7 to said axle 9. Preferably the said vertical portion 10 of the conductor is inclosed within said post and the axle 9 is also inclosed as will next be described 85 so neither of said parts will be exposed to the electrolytic solution in the tank.

Within the drum and preferably extending diametrically thereof is a bar 14 of insulating material fast at its ends to the cylindrical shell 15 of the drum and forming the support therefor upon the axle. This bar 14 provides an enlarged hub 16 at its middle taking over the axle and extending at the side toward the post substantially to 90 the plane of the edge of the shell. The said hub is spaced out from the post 7 by a filler block 17 which preferably has a boss 18 extending rotatably into the said post so as to obtain a tight joint for excluding the 95 solution from the axle. At the outer or free end of the hub, is a recess 19 within which the axle terminates and in which is a cotter pin 20, or other suitable means, passing through the axle for holding the drum 100 therein. This recess 19 is covered over with a cap 21 preferably made tight to exclude the 105 solution.

Preferably the bar 14 is bored longitudinally as at 22, said bore intersecting the 110 axle and having therein upon opposite sides of the axle plungers or brushes 23 which ex-

tend therefrom substantially to the shell 15. As shown, each of these brushes is reduced at its outer end, as at 24, and carries thereon a spiral spring 25 which presses against the shell and tends to press the brush toward the axle to obtain electrical contact therewith. Near the outer end of each of said brushes is a screw 26, or other contact means, which extends in the plane of the drum transversely of the bar from one edge thereof to said brush and has a wire 27 connected to it upon the outside of the bar, which wire is held at its other end by a screw 28 in the shell from which the 15 cathode obtains its electrical charge as will next be described.

The cathode preferably comprises a plurality of contact members arranged circumferentially upon the inside of the shell 15, 20 these members exposing each a small contact surface and at such part of the drum that the articles to be plated will cover and rub upon them a large part of the time during operation of the apparatus. Preferably, 25 arcuate carriers 29 are provided of insulating material, such as wood, which has the shape of and fits close against said shell, there being one of these carriers 29 upon each side of the bar 14. For contact members I have shown screws 30 at intervals 30 along this carrier with their heads exposed upon the side of said carrier toward the center of the drum and their other ends toward the shell having a wire 31 attached thereto for conducting current to each of 35 said screws or members 30. At one end of each carrier, the wire is connected to a plate 32 fast to said carrier on the side thereof toward the shell and adapted to be clamped 40 against the screw 28 in the shell so as to conduct current therefrom to the members 30. Preferably the carrier 29 incloses said plate 32, wire 31 and the screw ends of the members 30 so as to prevent access of the 45 solution thereto and thus prevent plating thereof. The carriers are removably mounted in the drum by suitable means such as screws 33, and in the operation of my improved apparatus, these carriers may be removed as occasion requires and dipped or otherwise treated for removing any plating which accumulates upon the exposed portions of the members 30. It is to be noted 50 also that I provide a block 34 to cover the screw 26 and wire 27 which conducts the current to the carrier from the brush 23. The current to the members 30 is in this way obtained from the cathode rod 12 through the extension 11 and upright portion 10 and 55 axle 9 by the brushes 23, contacting screws 26 and wires 27 by which the current is delivered to the screws 28 on the shell beneath the carrier 29 engaged by the plate 32 which is in turn connected by wires 31 to said 60 members 30. The shell preferably has cir-

cumferential series of perforations 35 upon opposite sides of the carriers 29 to permit the solution to drain out quickly when the barrel is raised out of the tank.

The ends of the barrel are preferably 70 closed by heads 36 of textile materials permeable to the electrolytic solution employed, although it is within the scope of the invention to substitute other materials if found more desirable. Said heads provide rings 75 37 upon which the material is secured and adapted to slip onto the outer circumference of the shell, holding the body portion 38 of the head tight across the end of the drum in the plane thereof. The head toward the 80 post 7 is preferably apertured at its center to permit the axle 9 to pass therethrough and is clamped between the hub 16 and the filler block 17. The other head is preferably removable and by taking this head off 85 the articles to be plated are inserted before treatment and are removed in the same manner when the treatment is finished. It is to be particularly noted that the articles rest upon the shell of the barrel and tumble 90 thereon, and that the weight of the articles is not materially upon the textile heads 36. During rotation of the barrel, the articles will be caused to tumble positively by the bar 14 which extends diametrically across 95 the barrel and which thus acts as an agitator to stir the mass of articles.

The stud shaft 4 is mounted upon an axle 39 which is preferably a rod bent at its end toward the post to extend longitudinally 100 of the vertical portion 10 of the conductor from the cathode bar to which portion said axle is shown bolted. For inserting the conductor in the post 7, said post has a longitudinal sheath 40 which is removable, said 105 sheath preferably being at the side of the post opposite from the axle.

For mounting the apparatus in a tank, I have shown longitudinal upper and lower beams 41, 42 respectively near the top and bottom of the tank parallel to each other. The upper of these beams is not over the lower one, but is off-set sufficiently to permit the post 7 to be stood upright with one beam upon one side and the other beam 110 upon the opposite side thereof. The back of the post, that is, the side thereof having the sheath 40, is positioned to rest against the upper beam, and upon the other side of the post at its bottom is a lip 43 adapted to 115 take under the lower beam. The upward pull on the belt 5 tends to hold the lower end of the post toward the lower beam and the upper end of the post toward the upper beam, the lip 43 preventing upward displacement. To remove the apparatus, the belt is run off the pulley, the cathode rod removed or swung aside as usual, and the apparatus lifted out. To facilitate this, I have shown a ring 44 at the top of the post al- 120 125 130

though this may be dispensed with and other means substituted as found desirable. Anode plates 45 are hung within the tank at opposite ends of the barrel upon rods 46, 5 and it is to be understood that the current passes by means of the electrolytic solution through the permeable drum heads to the articles to be plated. The solution is maintained at an elevation in the tank below the 10 pulley 6 and stud shaft 4 and may be as much lower as found desirable, although I prefer to substantially submerge the barrel as shown.

Obviously various modifications and 15 changes may be made in the manufacture of my improved apparatus without departing from the spirit and scope of the invention, and I do not wish to be understood as limiting myself except as required by the 20 following claims when construed in the light of the prior art.

Having thus described the invention, what I claim is,

1. In a plating apparatus, a barrel having 25 opposite ends permeable to liquid and an intermediate annular shell, a circumferential series of cathode members at the inner surface of said shell adapted to be engaged by articles tumbling within the barrel, connections extending circumferentially of the 30 inner wall of said shell between said cathode members, and means also extending circumferentially upon said inner wall of the shell for covering and protecting said connections and exposing said cathode members.

2. In a plating apparatus, a barrel having a peripheral shell, a carrier within said barrel and fitting against said shell, means removably securing said carrier in place, and 40 a cathode upon said carrier whereby said cathode may be removed from the barrel when desired.

3. In a plating apparatus, a barrel having a peripheral shell, a carrier within said 45 barrel and fitting against said shell, means removably securing said carrier in place, a plurality of cathode members upon said carrier, and means between the carrier and shell electrically connecting said cathode members.

4. In a plating apparatus, a rotatable barrel, a bar extending across said barrel for supporting the same, an axle transverse to said bar adapted to conduct electricity into the barrel, a brush adapted to rotate with the barrel in engagement with the axle, and a cathode in electrical connection with said brush.

5. In a plating apparatus, the combina-

tion with a tank, of a removable post adapted to be stood within said tank, supporting means at opposite ends and upon opposite sides of said post, a barrel on said post, and driving means for said barrel tending to swing the opposite ends of the post against 65 said supporting means thereby holding the post in upright position.

6. In a plating apparatus, the combination with a tank, of a removable post adapted to be stood within said tank, supporting 70 means at opposite ends and upon opposite sides of said post, said post having a lip at its bottom adapted to underlie the lower supporting means, a barrel on said post, and driving means for said barrel tending to 75 swing the opposite ends of the post against said supporting means thereby holding the post in upright position.

7. In a plating apparatus, the combination with a conductor having its ends bent 80 laterally with respect to its middle portion, one end forming an axle and the other end adapted to hang upon a cathode rod, a barrel rotatably mounted upon said axle, a cathode within said barrel, a brush adapted 85 to rotate in engagement with said axle and in electrical connection with the cathode whereby a circuit will be completed from the cathode rod to the cathode.

8. In a plating apparatus, a barrel having 90 opposite ends permeable to liquid and an intermediate annular shell, a circumferential series of cathode members at the inner surface of said shell adapted to be engaged by articles tumbling within the barrel, connections extending circumferentially of the 95 wall of said shell between said cathode members, and means also extending circumferentially upon said wall of the shell for covering and protecting said connections. 100

9. In a plating apparatus, a barrel having opposite ends permeable to liquid and an intermediate annular shell, a circumferential series of cathode members at the inner surface of said shell adapted to be engaged 105 by articles tumbling within the barrel, connections extending circumferentially of the wall of said shell between said cathode members, means for supplying current to said connections, and means for supporting and 110 rotating the barrel.

In testimony whereof I have signed this specification in the presence of two subscribing witnesses.

JOSEPH GIULIANA.
